Design No. 178.

Patrick Melony.
Design.
for Water Coolers. Patented Aug. 3, 1852. -

Des. 478

Patrick Molony of Cincinnati Ohio
Letters Patent No 478 Dated Aug 3 1852

The schedule referred to in these Letters Patent and making part of the same

To all whom it may concern:

Be it known that I Patrick Molony of the City of Cincinnati in the County of Hamilton and State of Ohio have invented or produced a new and original design for a Water Cooler and I do hereby declare that the following is a full, and exact description of the same reference being had to the accompanying drawings and to the Letters of reference marked thereon and said drawings making a part of this specification.

Similar letters refers to corresponding parts of the design in the annexed drawings.

Fig 1 is a side elevation showing the broad side of the Handle attached to the cover together with the cock.

Fig 2 is a horizontal sectional view through the centre of the cooler showing the finish of the ceiling and Pannels.

The following will be found a description of my improved designed water cooler, a. a fig 1 is the base of the cooler consisting of a group of various mouldings extending from the bottom of the cooler up to the panels (c c c c c) and ribs b. b. b. b. b. which extend from the base to the cap. etail mouldings e. e. the foresaid panels at the top between the ribs are furnished with arched pieces (d. d. d. d. d.) resembling the Gothic order to some extent the outlines of the upper part of which is bound by curved and undulating lines f f is the cover of the cooler made with a conical form and furnished with a curve T and bead.

2

Dec. 478

moulding K at the top under the ornamental oval shaped handle g as represented in the annexed drawings there is a lions head h, between two of the ribs at the lower part of the cooler furnished with a hole to receive a cock which is used for drawing water all of which is represented in the annexed drawings.

That I claim as my production and desire to have secured to me by Letter Patent is the design and configuration of an ornamental water cooler substantially as described and represented in the annexed drawings.
